RAIL FASTENING

Walter Kaempf, Berlin-Zehlendorf-West,
Germany

Application November 30, 1931, Serial No.
578,078, and in Germany December 9, 1930

2 Claims. (Cl. 238—304)

My invention relates to improvements in rail fastenings, and more particularly in a rail fastening comprising tie-plates and wedges for fixing the rail thereto. In constructions of this type a wedge is driven into position on one or both sides of the rail between one or both flanges of the rails and prongs or catches provided on the tie-plate.

The fastening of the rail by means of wedges is reliable and simple, and it results in a strong fastening. However, notwithstanding the great advantages of the construction, the fastening of the rails based on the use of wedges has not come into general use, the reason being that the practical and theoretical conditions of the said fastening have not been generally understood.

In fastenings of the type referred to, which are subject to continuous vibrations, it is important that the wedges and the members engaging the same make contact with their whole surfaces, and that they bear on each other not only with a few points or with two lines. In constructions heretofore proposed this prerequisite has not in any way been taken into consideration. Thus it has been suggested, for example, to drive the wedge between two parallel surfaces. Therefore, the wedge was at one side only in linear contact, which contact was in some cases confined to a very narrow surface by deformation of the material. A further deficiency of all the constructions heretofore in use was that in no way was care taken to compensate objectionable clearances which necessarily result from the inaccuracies of the parts manufactured on a large scale when assembling the same, so that bodies which theoretically should be in full surface contact, and the drawing of which showed such surface contact, practically made contact only along a line or with a few points.

The prongs or catches formed on the tie-plates are made exceedingly strong and solid and frequently they are reinforced by ribs thus providing a rigid and completely non-elastic body, which results in an excessive strain of the said parts and high surface pressure and rapid and non-uniform wear of the engaging elements. Therefore the fastening is rapidly made loose, which results in an enlargement of the gauge and other objections the repair of which requires expensive and difficult work.

Further, all those fastenings comprising wedges are objectionable in which the wedges are held in position by hooks which are fixed in holes made in the tie. By the vibration caused by the cars cracks are produced in the ties beginning from

the said holes. By such destruction of the material a strong joint is made impossible, and the wedges are rapidly made loose. The life of the ties is materially reduced, and the cost of the super-structure is increased. Also when using wooden wedges there is the danger of the structure becoming loose, even if between the foot of the prong and the edge of the base flange of the rail a fitting piece is inserted, and the wooden wedge is driven in from above to the base flange and laterally on the web of the rail and within a solid curved prong providing a rigid abutment. By providing a large number of elements the number of the possible clearances which interfere with a strong joint is increased.

The object of the improvements is to provide a fastening in which the aforesaid objections are obviated. In my improved construction I make use of normal ties having no holes, impressions or bulged portions for the prongs or catches. The iron tie-plates are welded to the ties or secured to wooden ties. They are provided each with two prongs or catches on which the wedges are supported with their whole bearing surfaces, the inner surfaces of the prongs or catches and the corresponding faces of the wedges having corresponding inclination and shape when the wedge has been driven on to the tie-plate, so that the said parts have large bearing surfaces. The prongs or catches are constructed so that they compensate for the difference in shape resulting from the unavoidable clearances and that the wedge and the prongs are in complete contact at their bearing faces. Such close engagement of the elements notwithstanding the difference in the dimensions is possible only if the prongs are able, by their elasticity and special shape, completely to adapt themselves to the shape of the wedge.

Therefore the prong is made elastic, and preferably it takes the form of a body in which the bending stress is alike throughout the length of the prong, and which is capable of being bent to a large degree, and which finally is adapted to take up the longitudinal and transverse forces. The degree of the necessary deformation by bending depends upon the clearances to be compensated for, and the material of the tie-plate is selected in accordance with the shape of the prongs and the necessary highest deformation. To permit a maximum bending deformation, the prongs are preferably constructed as beams of uniform resistance against bending.

In addition to the said features relating to struc-

ture and material, also the shape of the prong relatively to the wedge is important.

Before the wedge has been driven on to the tie-plate the contacting surface of the wedge and the prong have different curvatures. When the wedge is loosely set into the cavity of the prong or catch, the upper edge of the said prong or catch makes contact with the curved top part of the wedge along a line, because the prong and the wedge have equal pitch. By driving in the wedge the prong is bent outwardly at its top end, and the line contact is gradually changed to a surface contact. Thus the wedge is gradually driven into position while the prong is elastically bent outwardly, so that the surface contact is continuously increased. When the wedge is in final position, the surface contact is at its maximum. Now both parts have the same curvature, while before the radius of the curvature of the prong was smaller than that of the wedge. Therefore when the wedge is in final position, the prong and the wedge are in complete contact. The radii of curvature should be as large as possible, in order to obtain large lateral binding forces for the base of the rail.

After the wedge has been driven in and the joint has been made, the prong is under tension, while it is relieved of pressure when the wedge and the fastening are loose.

In order that my invention be more clearly understood an example embodying the same has been shown in the accompanying drawing in which the same reference characters have been used in all the views to indicate corresponding parts. In said drawing,

Fig. 1 is a sectional elevation showing the rail and its fastening.

Fig. 2 is a top plan view of Fig. 1.

Figs. 3 to 5 are detail sectional elevations showing the wedge in position, Fig. 3 showing the wedge loose, Fig. 4 showing the same partly driven in, and Fig. 5 showing the same in final position, and

Fig. 6 is a diagrammatic view showing the curvature of the prong and the deformation thereof.

As is shown in Figs. 1 and 2, the fastening comprises a rail *a*, a tie-plate *b* adapted to be secured to the tie, and formed with a pair of prongs or catches *c*, and wedges *d* engaging the prongs and the base flange of the rail.

As is best shown in Figs. 3 to 5, the prongs are formed with an inner curved face *c*¹, and the wedge *d* is formed with a corresponding curved face *d*¹ and with a longitudinal notch *d*² engaging the edge of the base flange of the rail. While the wedge *d* is in loose engagement with the prong *c* the radii of the curvature of the faces *c*¹ and *d*¹ are different, the radius of the curvature of the face *c*¹ being smaller than that of the face *d*¹. But when the wedge has been driven on into the final position shown in Fig. 5, the prong is deformed so far that the said curvatures are alike and the faces *c*¹ and *d*¹ are in full contact.

In Fig. 6 I have illustrated the shape and position of the prong, and more particularly of the inner curved surface *c*¹ in the two end positions of the prong, the broken line showing the shape of the face *c*¹ while the wedge is loose and the prong is not under tension, and the full line

showing the surface *c*¹ after deformation of the prong produced by the wedge *d* being driven on into final position. The line shown in full lines also represents the curvature of the wedge, and the area included between the full and broken lines represents the degree of the deformation of the prong. At such parts where the wedge or the prong does not exactly correspond to the correct shape, the prong yields in accordance with the inaccuracies and by reason of its elasticity it will follow the inaccuracies of both parts and cause close engagement at all parts and with the whole surfaces *c*¹ and *d*¹.

The angle of the wedge must be much smaller than the angle of friction of the iron. The said angle of friction is 12° 30', and therefore the angle of the wedge should be only one eleventh or one twelfth of the said angle, so that the pitch of the wedge is about 2.5%.

Figs. 3 to 5 show the position and shape of the prong and wedge in the different positions of the wedge, Fig. 3 showing the wedge loosely fitted between the prong and the base flange, Fig. 4 showing the same partly driven in, and Fig. 5 showing the same in final position.

The prong is gradually reduced in cross-section from its base towards its outer end, the said reduction being such that the bending stress is the same in all parts of the height of the prong. Further, the radius of the curvature of the surface *c*¹ of the prong is so much smaller than that of the surface *d*¹ of the wedge that after bending to compensate for the allowance, and after the wedge has been forced into final position, the prong and the wedge are in close contact with each other.

I claim:

1. In a rail fastening, the combination with a tie plate having an integrally formed upstanding elastic prong having an inner face adapted to extend generally in the direction of the rail flange, said face curving upwardly and inwardly toward the rail, of a wedge member coacting with the rail flange and the prong and having a face corresponding to and of initially greater radius of curvature than the face of the prong, whereby the insertion of the wedge between the rail flange and the prong flexes the latter to alter the curvature of the prong face to conform to that of the the wedge member.

2. In a rail fastening, the combination with a tie plate having an integrally formed upstanding elastic prong having an inner face adapted to extend generally in the direction of the rail flange, said face curving upwardly and inwardly toward the rail, of a wedge member coacting with the rail flange and the prong and having a face corresponding to and of initially greater radius of curvature than the face of the prong, the ratio of the radii of curvature of the cooperating faces of the wedge member and prong being such that the deformation of the prong on the driving of the wedge member into position ensures contact of the said cooperating faces over a major portion thereof.

WALTER KAEMPF.
